United States Patent

Des. 241,262
Patented Aug. 31, 1976

241,262

VEHICULAR TOY

Wayne Kuna, Oak Park, Ill., assignor to Marvin
Glass & Associates, Chicago, Ill.

Filed Apr. 9, 1975, Ser. No. 566,449

Term of patent 14 years

Int. Cl. D21—01

U.S. Cl. D34—15 AJ

Fig. 2

Fig. 3

FIG. 1 is a perspective view of a vehicular toy showing my new design;

FIG. 2 is a front elevational view thereof shown on a slightly enlarged scale;

FIG. 3 is a rear elevational view thereof;

FIG. 4 is a top plan view thereof;

FIG. 5 is a bottom plan view thereof; and

FIG. 6 is a side elevational view thereof, the side opposite of FIG. 6 being substantially identical thereto.

I claim:

The ornamental design for a vehicular toy, as shown and described.
